UNITED STATES PATENT OFFICE.

AUSTIN C. EVANS, OF SPRINGFIELD, OHIO.

HARROW.

SPECIFICATION forming part of Letters Patent No. 321,805, dated July 7, 1885.

Application filed February 9, 1885. (No model.)

To all whom it may concern:

Be it known that I, AUSTIN C. EVANS, a citizen of the United States, residing at Springfield, in the county of Clark and State of Ohio, 5 have invented certain new and useful Improvements in Harrows; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My invention relates to improvements in 15 harrows.

My invention relates to that class of harrows which have their sections flexibly connected together; and it pertains more particularly to three-section harrows, in which the 20 outside sections are operated by a longitudinal lever pivoted over the middle section, and connected by chains with the outside sections.

My invention consists in a single link connecting the operating-lever and the rear of the 25 middle section, to allow the lever to be thrown from side to side in operating the outside sections without disconnecting it from the rear end of the middle section, to allow the latter to be elevated thereby, and to cause the lever 30 to recover its normal position when let go by the operator.

Figure 1 is a top view of a three-section harrow with my improvement embodied therein. Fig. 2 is a rear elevation of the same. Fig. 35 3 is a side elevation of the middle section, and the lever thereon shown in its normal position. Fig. 4 is an enlarged view of the link in longitudinal elevation.

A is the middle section of the harrow, A' 40 A', the two outside sections hinged thereto.

B is the lever, which extends over the central longitudinal line of section A, its front end being loosely pivoted in a guideway on the front end of the section. It is connected 45 from either side with the outside sections by chains *a a*, and stands at an angle with the plane of the harrow, as seen in Fig. 3. It is held in its elevated position by means of a long link, *b*, (which connects the lever and the 50 rear end of section A together,) and by the tension of chains *a a*. In the normal position

of the lever the link *b* stands perpendicularly, as seen in Figs. 2 and 3. When the lever is thrown to one side to elevate a side section, as shown in dotted lines, Fig. 2, the link, 55 being pivoted at each end, is inclined more or less in the opposite direction, the lever describing a circular movement over the point where the lower end of the link is pivoted to bolt *c*. As soon as the lever is freed from the hand of 60 the operator and the lifted section falls to the ground or to the same plane with the other sections link *b* is pulled back to a perpendicular again, which brings the hand-lever B to its normal position.

The plates *d* and *d'*, in which the upper and lower ends, respectively, of link *b* are pivoted, consist of a malleable iron plate with a pair of ears or lugs thereon extending vertically therefrom; and the ends of the link being 70 formed in the manner of a bent ring, similar to a link of a surveyor's chain, a small bolt or pin, *c* and *c'*, is inserted through the holes in the ears and through the intermediate link end. By reference to Figs. 2 and 3 it will be 75 noticed that the lugs or ears of the plates *d* and *d'* stand transversely, so as to allow the link absolute freedom of movement toward either side of section A when lever B is operated. The upper plate, *d*, being inclined to 80 conform to the line of lever B, its ears project at something less than a right angle therefrom. It is bolted to the under side of the lever, as seen in Fig. 3. Plate *d'* is bolted to bar *d''*, which latter extends across the rear 85 end of section A, as is usual in the construction of this kind of harrow.

I do not claim a lever which is detachable, as the purpose of my lever is to retain it in an operative position with freedom of movement in either direction without detaching it from its support.

I claim as my invention—

1. In a three-section harrow having its sections hinged together and operated by a lever, 95 as specified, the combination, with the latter and the middle section, of a link pivotally connecting the same, whereby said lever is free to operate toward either side of said middle section in elevating the outside sections without changing its point of attachment to the latter or detaching it therefrom.

2. In a three-section harrow operated by a lever loosely pivoted at the front end over the middle section, and connected by chains with the outside sections, as set forth, the combination, with the lever, the chains, and the harrow-sections, of a link pivoted, respectively, to said lever and the rear of the middle section, whereby said lever is supported in its elevated position by said link and the tension of the chains, and is adapted to move freely around its pivotal connection in elevating said side sections without disconnecting it from its pivotal point of support on said middle section.
3. In a three-section harrow, a lever extend-

ing over the middle section, and chains connecting the same with the outside sections, a link pivotally connecting said lever with the rear of the section beneath it, said link being held in an erect position by the tension of the chains connecting said lever with the outside sections, and being free to incline toward either side in operating said lever, as set forth.

In testimony whereof I affix my signature in presence of two witnesses.

AUSTIN C. EVANS.
